(No Model.)

R. K. BOYLE.

AUTOMATIC TELEGRAPH.

No. 250,132.

Patented Nov. 29, 1881.

UNITED STATES PATENT OFFICE.

ROBERT K. BOYLE, OF BROOKLYN, ASSIGNOR TO DANIEL H. CRAIG, OF NEW YORK, N. Y.

AUTOMATIC TELEGRAPH.

SPECIFICATION forming part of Letters Patent No. 250,132, dated November 29, 1881.

Application filed March 24, 1881. (No model.)

To all whom it may concern:

Be it known that I, ROBERT K. BOYLE, a subject of the Queen of Great Britain, residing at Brooklyn, in the county of Kings and State 5 of New York, have invented new and useful Improvements in Automatic Telegraphs, of which the following is a specification.

This invention relates to a new method of producing signals by electricity, which consists 10 of a sheet-metal band, a new code of transmitting-signs produced on said metal band by means of a suitable non-conductor of electricity, and two springs which bear upon said metal band, and one of which is provided with a 15 sharp or narrow end, while the end of the other spring is extended or provided with a foot. The signs are composed of parallel strokes, some of which are shorter than the others, and at different distances apart, the long strokes being 20 in the path of the extended spring, while all the strokes are in the path of the narrow spring. Each of the springs is connected with the line and with a battery, and as long as either of said springs is in contact with the metal band 25 its battery is in a loop-circuit; but whenever one of said springs passes over one of the strokes of the transmitting-signs its battery is thrown on the line, and a corresponding signal is produced in the receiving-instrument of the 30 distant station.

This invention is illustrated in the accompanying drawings, in which Figure 1 represents a diagram of my automatic telegraph when the receiving-instrument consists of a 35 pen and a strip of chemically-prepared paper. Fig. 2 shows my code of signals.

Similar letters indicate corresponding parts.

In the drawings, the letter A designates a 40 band, made of sheet-brass or any other suitable metal, on which the messages to be transmitted are produced by painting or otherwise delineating thereon the appropriate signs taken from my new code of transmitting-signs. By reference to Fig. 2 it will be seen that these signs 45 are composed of parallel strokes, some of which are longer than the rest, and which are at different distances apart. The sign which is to produce in the receiving-station the letter "a" in the well-known Morse code of signals consists

in my transmitting-code of one short stroke and 50 one long stroke, the letter "b" of one long stroke and three short strokes, the letters "i" and "o" each of two short strokes, which, however, are at different distances apart, and so on, as will be readily seen from an examination of Fig. 2 55 of the drawings. For the purpose of producing the transmitting-signs on the metal band A, a material must be used which is a bad conductor of electricity, such as a solution of india-rubber or shellac.

The metal band A rests upon a metallic roller, C, which connects by a wire, 10, with one pole of a battery, B, the other pole of which connects with the line-wire 11. From the line-wire extends a wire, 12, to a spring, D, the free 65 end of which bears upon the metal band A. The wire 10 connects by a wire, 13, with one pole of a battery, B', the other pole of which connects by a wire, 14, with the earth. From the wire 14 extends a wire, 15, to a spring, D', 70 the free end of which bears upon the metal band A. The line-wire 11 connects with a metallic pen, which rests upon a metallic roller, G, that connects by a wire, 16, with the ground.

The free end of the spring D is in such a position that it meets only the long strokes of the transmitting-signs, and said end is bent so as to form a foot or extension, whereby the metallic connection between the spring and the metal band is broken for a certain period of 75 time whenever said foot rests upon one of a long stroke of one of the transmitting-signs, while the free end of the spring D' is in such a position that it meets the long strokes of the transmitting-signs simultaneously with the foot 80 of the spring D, and that it also meets all the short strokes of the transmitting-signs, the end of said spring D' being so formed that the metallic connection between it and the metal band is broken only momentarily at the instant 85 when it passes over one of the strokes. When both the springs D D' are in metallic contact with the metal band A, the batteries B B' are on loop-circuits, as follows: The current from battery B passes through wire 12, spring D, metal band A, roller C, and wire 10 back to the battery, and the current from battery B' passes through wires 13 10, roller C, band A,

spring D', and wire 15 back to the battery. But whenever the point of one of the springs passes over one of the strokes of one of the transmitting-signs the current of the corresponding battery is thrown on the line, and a mark is produced upon the chemically-prepared paper in the receiving-station, said mark being a stroke whenever the foot of the spring D passes over one of the long strokes in the transmitting-station, and a dot whenever the point of the spring D' passes over one of the short strokes in the transmitting-station. For instance, if the metal band A is moved forward in the direction of the arrow marked on it in Fig. 1, the point of the spring D' will first meet a short stroke of the transmitting-sign "f," the current of the battery B' is thrown on the line, and a dot is produced by the action of the pen E on the chemically-prepared paper; then the foot of the spring D will pass over the long stroke of the sign "f" and the current of the battery B is thrown on the line, thereby producing a stroke on the chemically-prepared paper corresponding in length to the length of the foot of the spring D; and finally another dot will be produced on the chemically-prepared paper as the point of the spring D' passes over the last short stroke of the sign "f" on the metal band. From this example it will be seen that by my code of transmitting-signs signals are produced on the chemically-prepared paper in the receiving-station corresponding to the letters of the Morse alphabet. Instead of the chemical

writing apparatus, an ordinary sounder may, however, be used in the receiving-station, and the signals are given by long or short sounds or pauses usual in Morse work. 35

By referring to Fig. 2 it will be seen that the form of my transmitting-signs is such that the same, with but little practice, can be produced on the metal band with great rapidity, either by the sender of a message or by the operator in the transmitting-station. 40

In Fig. 2, I have shown transmitting-signs for the twenty-six letters of the alphabet and for the sign "&," but it will be readily understood that the number of my transmitting-signs can be readily increased so as to include figures or any other characters. 45

What I claim as new, and desire to secure by Letters Patent, is— 50

The combination, substantially as hereinbefore described, of a metal band, non-conducting transmitting-signs marked on said band, two springs, one of which is provided with a foot and the other with a sharp or narrow end, two batteries, one for each spring, a line-wire including both batteries, and a suitable receiving-instrument. 55

In testimony whereof I have hereunto set my hand and seal in the presence of two subscribing witnesses. 60

ROBERT K. BOYLE. [L. s.]
